Attorneys

UNITED STATES PATENT OFFICE.

JAMES W. LANCASTER, OF SENATH, MISSOURI.

CHURN DASHER.

Application filed May 24, 1923. Serial No. 641,182.

To all whom it may concern:

Be it known that I, JAMES W. LANCASTER, a citizen of the United States, residing at Senath, in the county of Dunklin and State of Missouri, have invented certain new and useful Improvements in Churn Dashers, of which the following is a specification.

This invention relates to improvements in churn dashers, such as are ordinarily used 10 for churning butter.

The primary object of this invention is the provision of a churn dasher, which is relatively simple in construction, and which embodies propellers operable in opposite 15 directions upon reciprocatory movement of the dasher through a mass of liquid, as to effect a churning action both upon the up and down movements of the dasher.

A further object of this invention is the 20 provision of a dasher of the above mentioned character which is relatively simple in construction, embodying detachable parts which provide a structure which may be readily cleaned and is thereby highly desirable for 25 the purpose for which the same is provided.

A further object of the invention is the provision of a churn dasher of the above mentioned character, which may be used to economically churn butter, effecting the 30 churning in but a minimum of the time now required for churning by ordinary methods.

Other objects and advantages of this invention will be apparent during the course of the following detailed description.

35 In the accompanying drawing, forming a part of this specification, and wherein similar reference characters designate corresponding parts throughout the several views:

Figure 1 is a side elevation of the improved churn dasher, showing the handle portion thereof partly broken away.

Figure 2 is a fragmentary view, partly in cross section, showing the propeller end of the improved dasher, taken on the line 2—2 45 of Figure 1.

Figure 3 is a cross sectional view, taken substantially on the line 3—3 of Figure 2, showing improved features of a propeller used in connection with this invention.

50 In the drawing, wherein for the purpose of illustration is shown but the preferred embodiments of the invention, the letter A may generally designate the improved churn dasher which may include a handle B, propellers C and D; and means E for retain-

ing the propellers upon the handle so that the same may rotate in opposite directions.

Referring to the handle B, the same is preferably of wood or analogous material of light construction, and at its lower end 60 may be provided with an annularly reduced extension 10, as an integral part thereof, for receiving a sleeve or ferrule 11, as by means of a rivet 12 securing the same thereon; the outer surface of the ferrule 11 lying flush 65 with the outer surface of the major portion of the handle B. The ferrule 11, at its lower end, is preferably provided with a portion 14, having a tapped opening 15 extending upwardly therein, and continuing axially 70 through the extension 10 of the handle B for the detachable reception of the screw threaded end 16 of a bolt 17 for supporting the propellers C and D; the bolt 17 and the ferrule therefor preferably comprising a 75 portion of the means E for supporting the propellers C and D upon the handle B.

Referring to the propeller C, the same is preferably of two part construction, including parts 17^a and 18. The part 17^a includes 80 a hub portion 20 having the radial blades 21 and 22 oppositely extending therefrom; the hub portion 20 thereof being provided with a transverse groove 23 inwardly of the bottom face thereof, wherein may fit the hub portion 85 25 of the part 18. The part 18 includes the hub portion 25 having the propeller blades 27 and 28 radially extending outwardly therefrom. The hub portions 20 and 25 of the propeller parts 17^a and 18 respectively 90 are preferably provided with aligning openings 29 and 30 therein, which may receive the shank of the bolt 17 therein for rotation upon the shank. The hub portion 25 is of course relatively smaller than the hub portion 20 of 95 the part 17^a, but when the hub portion 25 of the part 18 rests within the groove 23 provided therefor in the hub portion 20 of the part 17^a, the blades 21, 22, 27 and 28 of the propeller C are all canted at the same angle 100 and in the same direction, so that upon drawing the propeller through a mass of liquid the same may be rotated by deflection of the liquid against the canted blades, as can be readily understood.

Referring to the propeller D, the same 105 preferably includes parts 35 and 36; the part 35 including a relatively large hub portion 38 having upon opposite sides thereof radially extending blades 39 and 40, and being 110

grooved inwardly from an end thereof with a transverse groove 42 for the snug reception of the hub portion 43 of the propeller part 36. The hub portion 43 of the part 36 is of course relatively smaller than the hub portion 38 of the other part 35, and is preferably of polygonal cross section for fitting within the groove 42. This hub portion 43 is preferably provided with 10 oppositely disposed propeller blades 47 and 48 thereon, so that when the parts 35 and 36 are assembled they will extend substantially at right angles to the alignment of the propeller blades of the part 35. Inwardly of 15 the hub portion 38, on the face thereof opposite to that face in which groove 42 is provided, it is preferred to provide a frusto-conical recess 50. The hub portions 38 and 43 are preferably provided with axial passageways 55 and 56 therethrough, which when the parts 35 and 36 are assembled are in alignment for reception of the shank of 20 the bolt 17.

Referring to the assembly of the propellers C and D in a definite relation, the propeller C is first assembled against the lower end 14 of the ferrule 11 and is rotatably disposed upon the shank of the bolt 17. In this relation the propeller D is below the 30 propeller C, with the smaller hub portions 25 and 43 of the propellers C and D respectively in abutting relation, and the head 57 of the bolt 17 and a washer 58 lying within the frusto-conical recess 50 and supporting 35 the propellers C and D in their rotatable relation upon the bolt 17. The blades 39, 40, 47 and 48, of the propeller D, are of course, all canted in the same direction.

The blades of the propellers C are inclined 40 in a direction opposite to the direction in which the blades of the propeller D are inclined, so that the propellers during their movement through a mass of liquid will move in opposite directions to effect a turning action.

From the foregoing description of this in-

vention, it is obvious that a churn dasher has been provided, which is relatively simple in construction, and the parts of which may be taken apart for cleaning purposes in 50 facile manner.

Various changes in the shape, size and arrangement of parts may be made to the form of invention herein shown and described, without departing from the spirit 55 of the invention or the scope of the claims.

I claim:

1. A churn dasher including a handle, and propellers rotatably mounted adjacent the lower end of the handle and positioned one 60 above the other, the upper propeller having a hub, a set of blades extending from the hub upon an axis extending at right angles to the axis of the handle, and a second set of blades extending from said hub and inclined 65 upwardly, the lower propeller having a hub, a set of blades extending therefrom upon an axis extending at right angles to the axis of the handle and a second set of blades inclined 70 downwardly.

2. A churn dasher including a handle, and propellers rotatably connected with the handle adjacent each other and positioned one above the other, each propeller having a hub and blades extending from the hub, 75 upon an axis at right angles to the axis of the handle, the propellers being provided with additional blades with the last mentioned blades of one propeller inclined upwardly and the last mentioned blades of the 80 other propeller inclined downwardly.

3. A churn dasher comprising a handle, and a propeller rotatably connected with the handle and having a hub, a set of blades extending radially from the hub and each upon 85 an axis extending at right angles to the axis of the handle, and a second set of blades extending radially from the hub and each upon an axis extending at an incline to the axis 90 of the handle.

JAMES W. LANCASTER.
